DESIGN FOR A WALL BRACKET

Marlin Waymack, Richmond, Va., assignor to Mitteldorf Straus, New York, N. Y.

Application March 8, 1943, Serial No. 109,697

Term of patent 7 years

To all whom it may concern:

Be it known that I, Marlin Waymack, a citizen of the United States of America, residing at Richmond, county of Henrico, and State of Virginia, have invented a new, original, and ornamental Design for a Wall Bracket, of which the following is a specification, reference being had to the accompanying drawing, forming a part thereof.

Fig. 1 is a perspective view of the wall bracket, showing my new design; and

Fig. 2 is a front elevational view thereof.

I claim:

The ornamental design for a wall bracket, as shown.

MARLIN WAYMACK.
